SURFACE HEATING UNIT WITH IMPROVED
HINGE AND GROUND CONNECTIONBen J. Vallorani, Melrose Park, Ill., assignor to
General Electric Company, a corporation of
New York

Application July 28, 1951, Serial No. 239,117

4 Claims. (Cl. 219—37)

1

This invention relates to heating devices such as the surface heating units of electric ranges, and it is an object of my invention to provide surface heating units having an improved hinge and ground connection for pivotally supporting the surface unit and grounding the heating elements thereof to the range frame.

Electric range surface heating units now commonly use heating elements of the sheathed conductor type as described, for example, in the C. C. Abbott U. S. Patent #1,367,341 dated February 1, 1921, and in the J. C. Sharp Reissue Patent #22,177 of September 8, 1942. The elements comprise a coiled resistance conductor housed in a metallic sheath and supported in insulated spaced relationship therewith by a densely compacted body of heat-conducting and electrically insulating material, such as powdered magnesium oxide. The elements are arranged in a flat coil pattern on a suitable support structure, with the terminal ends of the coils extending to a point of connection with the wiring system of the range, usually beneath the range cooking top. It is the accepted practice to hingedly secure the surface heating units to the range so that the units may be swung upwardly for cleaning or other purposes.

It is advantageous to secure the heating elements to the support structure in a manner allowing them maximum freedom of movement so that they may expand and contract relatively freely under temperature changes in use; and where practicable, it is desirable to secure the heating elements to the support structure at one point only, thus permitting maximum freedom consistent with proper securing to the support. My present invention provides a heating unit in which the terminal ends of the heating element are arranged for free movement, and the unit is secured to the range frame and grounded in a manner contributing to such freedom while at the same time resiliently restraining certain of the terminal ends against being lifted relative to the support structure. Specifically, I use a hinge having one element fixed to the frame of the range in electrically conductive relation, and another element rigidly attached to the support structure. A grounding member is welded or otherwise secured to the second-named hinge element and has a resilient conductor strip which extends parallel to a terminal portion of a heating element and permits movement of the terminal portion under normal heating and cooling conditions. Because the flexible grounding strip is an integral part of the hinge, it swings with the hinge when the surface unit is raised and there-

2

fore is not subjected to strains which might break or weaken the bond with the sheath of the heating element.

In the accompanying drawings, Fig. 1 is a fragmentary plan view of a surface heating unit utilizing a preferably preferred form of my hinge and ground strap; Fig. 2 is a side sectional elevation of the complete heating unit taken along the lines 2—2 of Fig. 1; Fig. 3 is a fragmentary end sectional elevation of the terminal portion of the heating elements, the terminal housing having been removed; and Fig. 4 is a perspective view of the combined hinge and ground strap secured to a support member of the heating unit.

15 In a typical installation, the heating units are mounted in a conventional electric range having a cooking top 1 provided with a suitable number of circular openings 2, each adapted to receive a heating unit 3. Usually, there are three or four 20 of such heating units suitably arranged about the cooking top.

25 The heating unit essentially comprises a first sheathed heating element 4 having the respective terminal portions 5 and 6, and a second sheathed heating element 7 having the terminal portions 8 and 9. The respective elements are of the aforementioned Abbott or Sharp type, pursuant to which each element has a coiled resistance conductor 10 housed in a metallic sheath 11 and 30 supported in uniformly spaced relationship to the sheath by a highly compacted mass 12 of a suitable heat-conducting and electrically insulating material, such as powdered magnesium oxide. As is conventional, the heating elements are arranged to form flat spirals of several coils and are nested one within the other on a support structure which may include a plurality of radially extending, vertically arranged, plates 14, 14a, 15, 15a, and 16, 16a joined together at a central hub and extending radially therefrom. Upper edges of these plates lie in a common plane and support the heating elements as shown.

35 The support structure is carried by a trim ring having a horizontal rim 17 resting on the cooking top 1 about the opening therein, and a downwardly extending flange 18, which is spaced inwardly from the depending flange 19 defining the cooking top opening 2. An advantageous manner of securing the support structure to the trim ring 40 is by providing each of the support arms with a short tongue 20 brought through a suitable slot in the trim ring wall 18. The trim ring thus establishes the plane of the upper edges of the support arms parallel to the plane of the cooking top 45 1. A drip and reflector pan 21 is suitably re-

movably supported below the heating unit as on an inwardly turned lip (see Fig. 2) at the base of the flange 19.

The respective heating elements rest on the upper edges of the support arms, and each element is secured to one only of the arms at only one point. As shown in Fig. 2, an outer convolution of each of the heating elements is anchored to the support arm 15a by an anchor plate 22 secured to the support arm and having upwardly extending pairs of jaws which grip the sheath of the respective heating elements. Except for this single point of attachment of the heating elements to the support structure, the elements are free to move on the upper edges of the supporting structures as they expand and contract with temperature changes. The terminal ends of the heating elements extend downwardly from the support arms and then through an opening 23 in the reflector pan 21. The terminal portions of the sheathed conductors extend for a substantial distance below the cooking top 1 and are provided with the illustrated exposed terminals 5, 5a, 6a, 8a, 9a. Terminals 6a and 9a have individual connection fittings 24, 25 to which the leads (not shown) of the range-wiring system may be attached by means of conventional binding screws 26; and as part of a conventional wiring circuit which provides for several levels of thermal output, the terminals 5a and 8a are permanently interconnected by a bus bar having the common connection fitting 27 as shown in Fig. 1.

It is a feature of my construction that the terminals are given maximum freedom of movement. Therefore, instead of the usual unitary drip shield which embraces all of the terminal portions, I apply individual metal drip shields 28 which tightly engage the outer sheath of said terminal portions. It will be noted that the terminal portions 6 and 9 may move relative to each other, and each of these terminal portions has freedom of movement relative to the terminals 5 and 8. Consistent with the objective of maximum freedom of movement, I use a porcelain terminal spacer block 29 which slips over the terminal ends of the terminals and is loosely held thereon merely by resting upon the heads of the connection screws. As is shown in Figs. 1 and 2, this block 29 is provided with wall means which define pockets accommodating the terminals.

It has previously been noted that each heating unit is hingedly mounted on the range frame; and it is well known that the sheaths of the individual heating elements must be grounded to eliminate shock hazard. I have provided a simple, effective, hinge having grounding means constructed as an integral part thereof, and have arranged said grounding means so that the terminal ends of the sheath have maximum freedom of self-adjustment and at least one terminal end of each heating element is resiliently restrained against accidental displacement relative to the support structure.

Referring now to Figs. 2 and 4, the combined hinge and ground strap 30 includes a hinge element comprising a rigid base plate 31, from which extends, preferably upwardly, a pivot plate 32, and spaced, rigid, attachment strips 33, 33a which are arranged to lie flush against the flange 19 around the cooking top opening. It will be understood that the cooking top comprises an element of the range frame and that when the range is installed its frame is electrically connected to ground by suitable means (not shown).

The hinge element is firmly secured to the range frame element by a self-tapping screw 34 or equivalent fastening means which will make electrical contact with the metal of the range frame, specifically with the base metal of the flange 19. The upper ends of the strips 33, 33a are curved to conform to the curved transition between the flange 19 and the cooking top; and with the illustrated stiffening ribs provided in base plate 31, which abut the lower edge of flange 19, provide means for quickly and easily locating the hinge element on the range. As shown in Fig. 3, the spacing between the strips 33, 33a easily accommodates the shank of screw 34, but provides for substantial engagement of the screw head with the plates. A washer (not shown) may be used beneath the screw head if desired, although experience indicates that it is unnecessary.

The complementary hinge member may advantageously comprise a rigid bar having an integral pivot plate 35 and an integral securement plate 36 at its respective ends. Plate 36 is preferably riveted to support arm 15, although it may be welded or otherwise secured thereto. Intermediate these plate-like members, the bar is shaped as necessary to position its longitudinally extending portion 37 substantially in the plane of the respective terminal portions 5, 6, 8, and 9 of the heating elements and in relatively close, laterally spaced, relationship to one of said terminal end portions. For example, in a surface unit having only one heating element, the portion 37 might be relatively close to one of the terminal end portions and widely spaced with respect to the other. In the illustrated two-element embodiment, the portion 37 runs centrally between the adjacent terminal portions 5 and 8. The respective hinge elements are pivotally joined by a metallic rivet extending through the pivot plates 32 and 35. I prefer to use a conventional frusto-conical metal friction washer 40 between the pivot plates so that the heating unit will be frictionally held in any position between its normal operating position and any raised position.

To ground the heating element sheaths while affording adequate freedom of movement of the terminal ends and providing resilient means to restrain separation of one end of each of the heating elements from the support structure, I use a novel ground strap having flexible members which run parallel to the terminal portions, and provide electrical connection between the rigid bar-like hinge element and the terminal sheath. As shown best in Fig. 4, the grounding means comprises a generally U-shaped metallic structure having a base portion 41 welded to a "flat" formed in the underside of the portion 37, and flexible strips 42, 43 preferably integral with the base 41 and extending beneath the terminal portions 5 and 8 in relatively close spaced relation, as appears in Fig. 2. So as to space the flexible strips suitably below the terminal portions, the base 41 is formed with suitable offsets, as indicated in Figs. 3 and 4. The downwardly extending tips 42a, 43a of the strips are welded to the drip shields of the terminal portions 5 and 8, and a positive electrical connection is thus made from the sheath of each heating element through the ground strip, the hinge, and screw 34 to the metal of the range frame. Although I have illustrated the grounding element as being of sheet metal stock, it is obvious that it might comprise a U-shape of spring wire, or that the strips 42, 43

might be replaced by spring wire lengths suitably secured to a base portion 41.

It should be noted that the respective heating elements, being in flat coil form, have an inherent resiliency. Because of this it may happen that one or the other of the terminal portions of each element may take a set during its manufacture which causes a short length of the actual operating portion of the element to lift above the support structure when the element is staked to the support member 15a. I have found that it is usually possible to true up the elements after staking by manually adjusting a terminal portion of one heating element with respect to its companion terminal portion. Also, I have found that occasionally the elements may be trued up by adjusting the terminal portion 5 of one element with respect to the terminal portion 8 of the other. In either case, it is advantageous to make this adjustment at the portions 5 and 8 by suitably bending the rigid bus bar 27. The flexibility of the ground strips 42, 43 permits such adjustment and serves to restrain the separation of these terminal portions from the support structure.

When the surface unit is in use the heating elements expand and contract, and in former constructions it was found that the rigid restraint of the ends of the heating elements (see, for example, the rigid interconnection of the heating element terminals by the unitary drip shield in the above-noted Sharp Reissue Patent #22,177) will cause intermediate portions of the heating elements to loop upwardly at some point along their operative length. In practice, this seriously affects the efficiency of heat transfer between the heating element and the cooking vessel placed thereon because an upwardly looping portion of an element will lift the bottom of the pan out of contact with a large portion of the heating surface. In the present invention, however, the complete freedom of the terminal ends 6 and 9, plus the large amount of freedom and flexibility afforded by the flexible ground strips at terminal ends 5 and 8, permit expansion and contraction of the elements while maintaining them in the horizontal plane of the support structure.

While there has been described what is at present considered to be the preferred embodiment of the invention, it will be understood that various modifications may be made therein, and it is intended to cover in the appended claims all such modifications as fall within the true spirit and scope of the invention.

I claim:

1. A surface heating unit for an electric range or the like, comprising, in combination, a support structure, a plurality of coiled tubular sheath heating elements mounted thereon, a single means secured to said support structure and engaging the sheath of each of said heating elements at one point only to secure the same to said support structure, said heating elements having rectilinear terminal portions extending in substantially parallel relation beyond said support structure, at least two of said terminal portions being structurally independent for movement relative to each other, a metallic hinge member having pivotally associated hinge elements respectively secured to said range and to the support structure, said hinge member being electrically connected to said range, and metallic ground strap means including a cross member rigidly electrically connected to, and extending angularly with respect to, said last-named hinge ele-

ment; and springable strips extending from said cross member, each of said strips being parallel to a different one of said terminal portions and in spaced relation therewith, the end of each said strip remote from the cross member being electrically connected to the sheath of its associated terminal portion.

2. For use with a heating unit for an electric range having a metallic body structure, said heating unit including a heating element comprising a resistance conductor having a coextensive metallic sheath electrically insulated therefrom, terminal portions of said metallic sheath being in relatively close proximity to said range body structure and having relatively free movement with respect thereto, and means including a rigid structural element secured to said metallic sheath intermediate the ends thereof for supporting said heating element relative to said range structure; a combined hinge and ground strap including a first metallic hinge member secured to said range body structure in electrically conductive relation therewith, a second metallic hinge member conductively pivotally attached at one end to said first member and secured at its other end to said structural element, said second hinge member extending longitudinally of at least one terminal portion of said metallic sheath in spaced relation therewith, a flexible conductor element secured at one end in conductive relation to said second hinge member intermediate the ends thereof and extending parallel to said one sheath terminal portion, and means for connecting the opposite end of said flexible conductor element in permanent electrically conducting relation to said metallic sheath at said terminal portion thereof.

3. For use with an electric range surface unit including a tubular sheathed heating element and support means for positioning said heating element substantially in the plane of an upper frame panel of said range, said support means having a rigid structural member and said heating element having substantially mutually parallel terminal portions extending therefrom below said structural member; a combined hinge and ground strap for pivotally mounting said unit relative to said range frame panel, comprising a metallic hinge member adapted to be secured to said range frame in electrically conducting relation therewith, a rigid metallic arm member pivotally attached to said hinge member and adapted for securement to said support means, and a relatively long, springable, metal ground

strap fastened at its respective ends to said hinge arm member and to the sheath of a terminal portion of said heating element, the intermediate portion of said ground strap extending axially along said sheath in spaced relation thereto, said ground strap resiliently resisting the separation of said heating element from said support structure.

4. For use with an electric range surface unit including a tubular sheathed heating element and support means for positioning said heating element substantially in the plane of an upper frame panel of said range, said support means having a rigid structural element and said heating element having a plurality of substantially mutually parallel terminal portions extending therefrom below said structural element; a combined hinge and ground strap for pivotally mounting said unit relative to said range frame panel, comprising a metallic hinge member adapted to be secured to said range frame in electrically conducting re-

lation therewith, a rigid, metallic, arm member pivotally attached to said hinge member and extending between adjacent terminal portions, said arm member being adapted to be secured to said support means structural element, and metal ground strap means including a rigid member electrically connected to said hinge element and extending transversely thereof and springable metal portions extending from said member in parallel, spaced relationship with the said adjacent terminal portions, each said springable metal portion being electrically connected to the sheath of a different one of said terminal portions and resiliently resisting vertical movement of said terminal portion relative to said hinge 15 arm member.

BEN J. VALLORANI.
